SAFETY RAZOR

Georges Monnet, Washington, D. C., assignor to
Guardian Merchandising Corporation, Mon-
treal, Quebec, Canada, a corporation of Quebec,
Canada

Application May 12, 1942, Serial No. 442,621

2 Claims. (Cl. 30—83)

This invention relates to safety razors, and refers more particularly to means for covering the edges of razor blades carried by the razors.

This application is a continuation-in-part of my co-pending U. S. patent application Serial Number 421,270, filed December 2, 1941, since matured into Patent No. 2,320,374, dated June 1, 1943, describing a safety razor having two clamping members which are connected with two levers and which may be moved through the central opening of a double-edge razor blade by the pressure of clamping means engaging these two levers, whereby the clamping members clamp this blade upon a guard.

An object of the present invention is to improve the construction of safety razors not only of this type, but of many other types as well, through the provision of suitable means for covering the edges of razor blades carried by the razors, thereby protecting from injury the users of such razors.

Another object is to combine means covering the edges of razor blades with means varying the type of shave possible with such blades.

A further object is the provision of a safety razor having edge-covering means which serve at the same time for facilitating the cleansing of the razor.

Other objects of the present invention will become apparent in the course of the following specification.

In accomplishing the objects of the present invention it was found desirable to provide a safety razor carrying elongated covering elements, which may be pivotally mounted upon the corresponding edges of the guard and which are used to cover the sharp edges of a razor blade mounted upon the razor. These covering elements may have eccentric surfaces extending closer to or further away from the sharp edges of the blade, depending upon the position of the covering element. The variation will affect the shaving operation, making it possible to have closer or less close shaves without changing greatly the pressure exerted by the hand of the user.

The cleaning of the razor is facilitated since the turning of a covering element will expose those surfaces which receive soap and hair particles during the shaving.

The invention will appear more clearly from the following detailed description, when taken in connection with the accompanying drawings showing, by way of example, preferred embodiments of the inventive idea.

In the drawings:

Figure 1 shows in side elevation a safety razor in its clamping position;

Figure 2 is a transverse section through the

head of the safety razor, in its inoperative position;

Figure 3 is a top view of the safety razor;

Figure 4 is a top view of a razor having differently constructed covering elements;

Figures 5 and 6 are a section and an end view, respectively, showing the covering element of Figure 4 in different positions.

The safety razor shown in Figures 1, 2 and 3 of 10 the drawings comprises a handle 10 which may be hollow and/or filled with a light-weight fluid and which may be provided with a number of suction cups 11 (Fig. 1) for attaching the razor to any suitable surface, such as the edges of a

15 bath tub.

The head of the razor includes a U-shaped frame 12 having a transverse piece 13 which is firmly connected to the handle 10 and two legs or frame posts 14 and 15 having convex top surfaces 16 and 17, respectively (Figs. 1 and 2). The frame post 14 is provided with an arcuate slot 18, while a similar slot 19 is formed in the frame post 15.

A rod 20 extends between the frame posts 14 and 15 and is used as a pivot rod for the levers 21 and 22 which actuate the clamping members 23 and 24, respectively. Two guide rods 25 and 26 also extend between the posts 14 and 15 and have top surfaces which constitute a continuation of the surfaces 16 and 17 of the posts 14 and 15. The lower arcuate surfaces 27 and 28 of the guide rods 25 and 26 constitute guides over which the clamping members 23 and 24 slide. The guide rods 25 and 26 are separated 30 from each other by a space 29 through which the clamping members 23 and 24 extend.

The lever 21 which is similar in shape to the lever 22, has a downwardly extending finger-engaged portion 30, a sleeve 31 mounted on the 40 rod 20, an intermediate portion 32, a transverse portion extending through the slots 18 and 19, and upper posts 34 provided with slots 35. The lever 22 which is also mounted on the rod 20, has a similar downwardly extending finger-engaged portion 36 and upper posts 37 provided with slots 45 similar to the slots 35.

Arcuate resilient clamps 39 have ends engaging the levers 21 and 22 and pressing them one against the other, so that the levers 21 and 22 are maintained by the clamps 39 in the operative position shown in Figure 1.

The lever 21 is connected and movable along with a frame-like guard portion 40. A similar guard portion 41 is connected with the lever 22.

55 In the clamping position shown in Figure 1, the guard portions 40 and 41 form a substantially continuous blade-supporting surface, so that a blade 42 may be conveniently clamped between the guard portions 40 and 41, and the clamping members 23 and 24.

A concave elongated finger-protecting element 43 extends along the outer edge of the guard portion 40 and is pivoted at 44 thereon. The member 43 hangs downwardly in the inoperative position of the razor shown in Figure 2. However, after the clamps 39 have moved the parts to the operative clamping position shown in Figure 1, a sharp edge of the blade 42 may be conveniently covered by the member 43 which is swung upwardly about its pivots 44. The opposite sharp edge of the blade 42 may be covered by a similar finger-protecting element 45 which is pivoted at 46 to the outer edge of the guard portion 41.

The arcuate clamping members 23 and 24 are similar to each other in form and may be resilient either totally or in part. The members 23 and 24 which extend through the space 29 between the guides 25 and 26, have clamping edges 47 and 48, respectively. In the inoperative position shown in Figure 2, the clamping edges 47 and 48 are situated one next to the other, so that a blade 42 may be conveniently placed upon these edges which will extend through the central opening 49 of the blade. As soon as manual pressure upon the finger-engaging lever portions 30 and 36 is released, the pressure of the clamps 39 will move the levers 21 and 22 toward each other. The clamping member 23 is connected with the lever 21 by pins 50 which are integral with the member 23 and which extend through slots 35 provided in the posts 34 of the lever 21. Pins 51 which are integral with the clamping member 24, extend through similar slots provided in the posts 37 of the lever 22. Thus a movement of the levers 21 and 22 toward each other will swing the clamping members 23 and 24 about the guides 25 and 26 and will move them through the central opening 49 of the blade 42 until the edges 47 and 48 of the clamping members will engage the blade 42 and press it firmly against the guard portions 40 and 41, thereby clamping the blade.

The operation of the razor is apparent from the above description. The clamps 39 normally hold the parts of the razor in the operative clamping position shown in Figure 1. In order to move these parts into the inoperative position shown in Figure 2, the user merely presses the finger-engaged lever portions 30 and 36 toward each other. The levers 21 and 22 then swing away from each other while being guided in the slots 18 and 19, and the guard portions 40 and 41 move along with the levers 21 and 22. Since the clamping members 23 and 24 are connected with the levers 21 and 22 by the pins 50 and 51, the levers will cause the clamping members to swing about the guides 25 and 26 and to withdraw through the central opening 49 of the blade 42 and the space 29 into the interior of the frame 12 until the clamping members reach the position shown in Figure 2.

Then the used razor blade may be conveniently removed and replaced by a new one.

As soon as manual pressure upon the lever portions 30 and 36 is released, the clamps 39 will move the razor parts back to the clamping position shown in Figure 1.

Figures 4 to 6 show a concave elongated finger-protecting element 60 which extends along the outer edge of a guard 61 of a razor. The element 60 has a curved spade-like portion 62 and a round tube-like portion 63 which is eccentrically mounted upon a pivot or rod 64. The portion 62 may be extended beyond the razor to facilitate the manipulation of the element 60. The pivot 64

extends through supporting portions 65 and 66 of the guard 61 and has a head 67 engaging the supporting portion 65. The opposite end of the pivot 64 is threaded and carries a nut 68, so that the pivot is held in place.

The portion 63 of the element 60 fits between the guard portions 65 and 66 and has outer surfaces 69 which approach or recede from the edge portion 70 of a razor blade 71 which is pressed by a clamp 72 against the guard 61.

Figure 5 shows the element 60 in its completely withdrawn position, in which a space 73 is provided between the cutting edge 70 of the blade and a surface 74 of the element 60. It is apparent that soap and hair particles are deposited upon the surface 74 during the shaving.

In the position shown in Figure 6, the surfaces 69 have been moved toward the edge 70, thereby closing the space between the cutting edge 20 and the element 60. Thus the angle at which the razor meets the skin of the shaver is changed. It is apparent that a closer shave is attained when the element 60 is in the position shown in Figure 5 than when it is in the position shown in Figure 6, if manual pressure remains about the same.

The element 60 is swung upwardly after the shaving until it is prevented from further movement in that direction by the engagement of the outer surfaces 69 with the adjacent edge of the guard 61. At that time, the surfaces 74 which receive soap and hair particles during the shaving, are so exposed that they can be conveniently wiped to remove the soap and hair particles. In its upward position, the element 60 serves as an adequate protector of the cutting edge 70 to preserve the sharpness of that edge 70 and to prevent injury to any person grasping the razor.

It is apparent that the specific illustrations shown above have been given by way of illustration and not by way of limitation, and that the structures above described are subject to wide variation and modification without departing from the scope or intent of the invention. All of such variations and modifications are to be included within the scope of the present invention.

What is claimed is:

1. In a safety razor, a blade-supporting member having at least one elongated edge, said blade-supporting member being adapted to carry a razor blade having a cutting edge extending parallel to said elongated edge upon said blade-supporting member, an elongated finger-protecting element, means carried by said blade-supporting member for swingably supporting said finger-protecting element adjacent said elongated edge, said finger-protecting element being swingable to a position wherein it covers said cutting edge of the blade, and clamping means for pressing said blade against said blade-supporting member.

2. In a safety razor, a blade-supporting member having at least one elongated edge and being adapted to carry a razor blade having a cutting edge extending close to said edge of the blade-supporting member, and a covering element having a curved elongated portion adapted to extend over said cutting edge, and another portion pivotally connected with said blade-supporting member.

GEORGES MONNET.
